UNITED STATES PATENT OFFICE.

NEWTON S. HUBBELL, OF MECHANICSVILLE, IOWA.

SPECULUM AND DILATOR.

SPECIFICATION forming part of Letters Patent No. 281,880, dated July 24, 1883.

Application filed June 2, 1883. (Model.)

To all whom it may concern:

Be it known that I, NEWTON S. HUBBELL, a citizen of the United States of America, residing at Mechanicsville, in the county of Cedar and State of Iowa, have invented certain new and useful Improvements in Speculums and Dilators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain new and useful improvements in that class of surgical instruments known as "speculums," and more especially to the sub-class of speculums termed "lateral dilators," or those in which only two wings are employed; and the object of my invention is to provide an adjustable lateral dilator which is adapted to be used in connection with any bifurcated speculum, or independently without being used in connection with a speculum, its use being evident to skilled practitioners; and this invention consists in the means employed for carrying out the object of the same, and in the construction, shape, and combination of the parts, as will be hereinafter set forth, and illustrated in the accompanying drawings, in which—

Figure 1 is a perspective view. Fig. 2 is a front view; Fig. 3, a plan view, showing the wings extended in dotted lines; and Fig. 4 is a detailed view.

This invention relates more especially to an improvement upon that class of dilators which includes the speculum known as "Bozeman's," which is well known and has been in use since the year 1658; and it consists in providing the speculum with a narrow handle or shank and spoon-shaped blades, which are provided at their ends with finger-rests, the shank of said blades being provided with upright pillars, to which are pivoted cross-bars, and are provided with means for adjusting the same laterally, both in regard to the end of the spoon and the handle thereof.

My invention further consists in the construction and combination of the parts whereby a ready and effective means for adjusting the spoons or dilators is provided, which con-

struction will be hereinafter set forth, and is fully illustrated in the annexed drawings.

In the annexed drawings, A A represent the 55 blades of my improved lateral dilator, the portion *a* being concave in cross-sections and slightly curved longitudinally. This spoon-shaped portion *a* is perfectly smooth on its exterior or convex side, and to the inner portion 60 thereof is secured a suitable shank, *b*, which is curved, as shown, and is provided at its outer end with a flattened portion, *c*, which form suitable grasping means or finger-rests for dilating the blades. To the front of these finger-pieces 65 *c*, as shown, are secured vertical pillars or standards *d*, which are bifurcated at their ends, so as to embrace the handle and the angular slotted arms *e*, attached to the upper portion of the aforesaid vertical standard *d*. 70 To the front of these standards are pivoted flat hinges, having their upper portion bent, so as to extend at right angles with the base of the hinge and standard *d*. The horizontal or upper portion of these hinges is provided with slots *f*', and with projecting lugs *d*' upon one of the hinges, while the opposite hinge is provided with lugs *g* *g*, which extend forwardly on the rear horizontal slotted arm and overlap the side of the forward arm. 75 This rear arm, *f*, is provided at one end with a bent portion near the standard *d*, while the outer end of the opposite horizontal end is curved, so as to lie within this offset or bent portion, as fully shown in the annexed drawings. 80 The two wings or arms of this dilator are secured to each other by means of a single bolt, which is provided on its inner end with a cut-away portion, *h*, the sides being flat and the ends screw-threaded, so as to receive a 85 suitable nut, *h*', the portion between the shoulder and the nut *h*' being of a length equal to the width of the horizontal arm *f*, and the flattened portion resting within the slots *f*', and bearing upon the upper and lower portions 90 thereof. The outer end of this bolt *H* passes through the slot in the arms *e* *e*, which are rigidly attached to the standard *d*, and this bolt, at its outer end, is screw-threaded and provided with a thumb-nut, *i*. It will be seen 95 by this construction that by loosening the nut *h*' the outer end of this dilator can be adjusted laterally to an extent double the length of the slot *f*', and when said nut is tightened the

parts are secured rigidly to each other. The ends or spoon-shaped portions of this dilator are adjusted laterally by means of the set-screw *i*, which bears upon the slotted bars *e*.

5 It will be noticed in this implement that the operating or adjusting parts are raised above the plane of the blade or spoon, and will not obstruct the view, and that the different adjustments are independent of each other, which 10 is important in special cases when the exterior portion of the opening in which the dilator is inserted is oversensitive; and by the construction hereinbefore described this dilator is adapted to be used in such operations as are 15 necessary to be performed upon virgins without disastrous results, and I believe that I am the first to construct a dilator which can be used in such cases.

It will also be noticed that the ends of the 20 spoon are extended without stretching unduly the exterior portion.

Having thus described my invention, the 25 advantages of which will be obvious to the skillful practitioner, I do not wish to confine myself to the precise construction herein shown, but reserve the right to modify the same without departing from the spirit of my invention.

It will be readily seen that this dilator is 30 adapted to be used in connection with any or all bivalve speculums for the purpose of making lateral dilations of the vagina, and thereby, when used in such connection, answering all the purposes of a four-valve speculum, with 35 the advantages of independent adjustment, as

the antero-posterior and lateral dilations are independent of each other.

The construction of this dilator may be varied so as to be used as a dilator for the cheeks, when it is desired for dental purposes in filling the molar teeth. 40

What I claim as new, and desire to secure by Letters Patent, is—

1. A bivalve dilator having blades or adjustable arms, with spoon-shaped portion *a*, 45 shank *b*, and handle or finger-rest *c*, connected to each other, for the purposes set forth.

2. The blades or dilators *A*, provided with standards *D*, secured rigidly thereto, and slotted transverse arms *e*, in combination with 50 the hinged connecting means *f*, having transverse slotted portion, and means for uniting the parts adjustably to each other, as herein set forth.

3. In a bivalve dilator, the dilators *A*, with 55 spoon-shaped ends *a* and finger-rests *c*, provided with upright standards *d*, having bent and slotted blades *e* rigidly attached thereto, in combination with the transverse slotted bars *f*, hinged to the pillars *d*, the parts being 60 united, so as to be capable of independent adjustment, by means of the bolt *H*, with set-screws, the parts being organized and adapted for the uses hereinbefore described.

In testimony whereof I affix my signature in 65 presence of two witnesses.

NEWTON S. HUBBELL.
